Specification of Letters Patent.

Patented Jan. 9, 1917.

Application filed March 20, 1916. Serial No. 85,447.

To all whom it may concern:

Be it known that I, ABRAHAM SCHWARTZMAN, a citizen of the United States, residing at the city of St. Louis, State of Missouri, have invented a certain new and useful Improvement in Bracelets, of which the following is a specification, reference being had to the accompanying drawing forming a part thereof.

10 This invention relates generally to jewelry and, more particularly, to a certain new and useful improvement, in jewelry bracelets, the principal object of my present invention being to provide an attractive 15 and comparatively simple and inexpensive expansible bracelet of the endless or so-called "Nethersole" type.

With the above and other objects in view, my present invention resides in the provision 20 of an expansible bracelet comprising a plurality of elastic units permanently connected together in ring form and in certain novel features of form, construction, arrangement, and combination of parts, all 25 as will hereinafter be described and afterward pointed out in the claims.

In the accompanying drawing, which illustrates my invention in preferred form, Figure 1 is a side elevational view of an 30 expansible bracelet embodying my invention, the bracelet being shown in normal or contracted condition; Fig. 2 is a side elevation view of the bracelet in abnormal or expanded condition; Fig. 3 is an enlarged 35 fragmentary plan view of the bracelet in abnormal or expanded condition; Fig. 4 is a through the bracelet in normal or contracted condition; Fig. 5 is a similar view 40 through the bracelet in normal or contracted condition; Fig. 6 is also an enlarged fragmentary sectional view through the bracelet in normal or contracted condition, but taken at right angles approximately to 45 the sectional view of the bracelet shown in Fig. 5; Figs. 7 and 8 are perspective views, respectively, of the outer and inner members of one of the bracelet-units or links; and Fig. 9 is a transverse sectional view 50 through the bracelet on approximately line 9-9, Fig. 3.

Referring to the said drawing, in which like reference characters refer to like parts throughout the several views, my new bracelet 55 comprises a plurality of similar expansi-

ble units or links preferably permanently connected together in endless or ring form, as illustrated particularly in Figs. 1 and 2.

Each of the units or links of the bracelet includes an outer preferably tubular member or casing 1 open at its ends. This member or casing 1, which may be of any suitable material preferably metallic, is preferably somewhat elliptical in shape in end elevation, as seen particularly in Fig. 7, and is lengthwise or longitudinally suitably arched or curved on any suitable radius, so that, when united in finished or bracelet form, the several units will provide an attractive endless ring of the desired diameter, the several units neatly and uniformly meeting and matching at their ends, as seen in Fig. 1, when the bracelet is in normal or contracted condition. Integral with, or fixed to, casing 1 and extending interiorly 75 thereacross at one end thereof, is a cross-piece or limiting stop 2.

Fitting within the casing 1 is a correspondingly arched or curved also preferably metallic inner unit-member 3. This 80 member 3, which is also tubular, preferably tapers lengthwise and is preferably closed or otherwise formed at its smaller or reduced end to provide a spring-abutment, as at 4, member 3 at its larger end being also 85 and correspondingly elliptical in end elevation and of such outside dimension as to fit smoothly within the end of an adjacent casing 1. Lengthwise from its said larger end, as seen particularly in Fig. 8, member 3 is 90 cut away to provide a pair of alining slots 5 adapted to fit cross-piece 2 of casing 1 and with the end wall of which slots 5 said cross-piece 2 is adapted to engage when the bracelet is in fully expanded condition. Fitting lengthwise and preferably loosely within member 3 is an elastic or resilient member preferably in the form of a coiled spring 6, one end of spring 6 abutting against closed end or stop 4 of the member 3 and the 100 other end of spring 6 abutting against cross-piece or stop 2 of member 3 or casing 1 when member 3 is operatively fitted within casing 1.

In operatively assembling the several 105 units or links, an inner member 3 with its spring 6 is lengthwise slidably fitted in an outer member or casing 1, the larger end of member 3 being presented toward, and the slots 5 thereof engaging loosely with, 110

the cross-piece 2 of said casing 1. Inner member 3 is now suitably forced outwardly relatively to member 1 and against the tension of spring 6, spring 6 in such movement 5 of member 3 being compressed between end wall 4 of member 3 and cross-piece 2 of casing 1, and the projected end of member 3 fitted within, and soldered or otherwise preferably permanently and rigidly fixed 10 to, the end of an adjacent outer casing or member 1, and so on throughout the several units or links of the bracelet.

The bracelet being so formed, it will be evident that the several outer members or 15 casings 1, on outward pull upon the bracelet, will expansively move upon, or relatively to, inner members 3 against the tension of, and compressing between the respective cross-pieces 2 and inner-member end-walls 20 4, the several springs 6, the expanding movement of the several casings 1 being approximately equal to the combined length of the several pairs of slots 5 of inner members 3 and the expanding movement of each casing 1 being limited by the engagement of 25 its cross-piece 2 with the end wall of the pair of slots 5 of its inner member 3. On expanding pull upon the bracelet being released, the several casings 1 will, under the 30 expansion of the springs 6, return to normal or bracelet-contracted condition.

Thus I provide an attractive bracelet of the endless or so-called "Nethersole" type which may be readily suitably expanded to 35 be easily slipped over the hand to fit upon the wrist.

I am aware that minor changes in the form, construction, arrangement, and combination of the several parts of my new 40 bracelet may be made and substituted for those herein shown and described without departing from the nature and principle of my invention as defined in the appended claims.

45 Having thus described my invention, what I claim and desire to secure by Letters Patent is:

1. An expansible bracelet or the like comprising a plurality of units, each unit including an inner tubular member provided with a spring abutment, an outer tubular member also provided with a spring-abutment, said outer member fitting around and being movable upon said inner member and the inner member of one unit being rigidly fixed at one end to and within the adjacent end of the outer member of the next unit, and a spring disposed wholly within said inner member and between the abutments 55 of said inner and outer members, said spring being compressed on expanding movement of said outer member upon said inner member.

2. An expansible bracelet or the like comprising a plurality of units, each unit in-

cluding an inner tubular member provided with a spring-abutment, an outer tubular member also provided with a spring-abutment, said outer member fitting around and being movable upon said inner member and the inner member of one unit being rigidly fixed at one end to and within the adjacent end of the outer member of the next unit, and a spring disposed wholly within said inner member and between the abutments 70 of said inner and outer members, said spring being compressed on expanding movement of said outer member upon said inner member, the abutment of said outer member being adapted to engage with said inner member to limit expanding movement of 75 said outer member upon said inner member.

3. An expansible bracelet or the like comprising a plurality of units, each unit in-

cluding an inner approximately tubular member closed at one end and slotted lengthwise inwardly from its opposite end, an outer member fitting around and movable upon said inner member, the inner member of one unit being fixed at its slotted 80

end to the adjacent end of the outer member of the next unit, a cross-piece on said outer member fitting in the slot of said inner member and adapted to engage the end wall of said slot to limit the expanding 85

movement of said outer member on said inner member, and a spring within said inner member, said spring being interposed between the closed end of said inner member and said cross-piece and being com- 90

pressed on expanding movement of said outer member on said inner member.

4. An expansible bracelet or the like comprising a plurality of units, each unit in-

cluding an inner approximately tubular member closed at one end and having a pair of alining slots extending lengthwise inwardly from its opposite end, an outer approximately tubular open-ended member fitting around and movable upon said inner member, the inner member of one unit being fixed at its slotted end to and within the adjacent end of the outer member of the next 100

unit, a cross-piece on said outer member fitting in the slots of said inner member, said cross-piece being adapted to engage the end wall of said slots to limit the expanding 105

movement of said outer member on said inner member, and a coiled spring lengthwise fitting within said inner member, said spring being interposed between the closed end of 110

said inner member and said cross-piece and being compressed on expanding movement of said outer member on said inner member.

5. In an expansible bracelet or the like, a unit including an inner tubular member pro-

vided with a spring abutment, an outer tubular member also provided with a spring abutment, said outer member fitting around and being movable upon said inner member 115

and being compressed on expanding movement of said outer member upon said inner member.

6. In an expansible bracelet or the like, a unit including an inner tubular member pro-

vided with a spring abutment, an outer tubular member also provided with a spring abutment, said outer member fitting around and being movable upon said inner member 120

and being compressed on expanding movement of said outer member upon said inner member.

7. In an expansible bracelet or the like, a unit including an inner tubular member pro-

vided with a spring abutment, an outer tubular member also provided with a spring abutment, said outer member fitting around and being movable upon said inner member 125

and being compressed on expanding movement of said outer member upon said inner member.

8. In an expansible bracelet or the like, a unit including an inner tubular member pro-

vided with a spring abutment, an outer tubular member also provided with a spring abutment, said outer member fitting around and being movable upon said inner member 130

- and said inner member being adapted to be rigidly fixed at one end to the adjacent end of the outer member of the next unit of the bracelet, and a spring disposed lengthwise wholly within said inner member, said spring being interposed between the abutments of said inner and outer members and being compressed on expanding movement of said outer member on said inner member.
6. In an expansible bracelet or the like, a unit including an inner tubular member provided with a spring-abutment, an outer tubular member also provided with a spring-abutment, said outer member fitting around and being movable upon said inner member and said inner member being adapted to be rigidly fixed at one end to and within the adjacent end of the outer member of the next unit of the bracelet, and a spring disposed lengthwise wholly within said inner member, said spring being interposed between the abutments of said inner and outer members and being compressed on expanding movement of said outer member on said inner member, the abutment of said outer member being adapted to engage with said inner member to limit expanding movement of said outer member on said inner member.
7. In an expansible bracelet or the like, a unit including an inner approximately tubular member closed at one end and slotted lengthwise inwardly from its opposite end, an outer member fitting around and movable upon said inner member, said inner member being adapted to be fixed at its slotted end to the outer member of the next unit of the bracelet, a cross-piece on said outer member fitting in the slot of said inner member and adapted to engage the end wall of said slot to limit the expanding movement of said outer member on said inner member, and a spring within said inner member, said spring being interposed between the closed end of said inner member and said cross-piece and being compressed on expanding movement of said outer member on said inner member.
8. In an expansible bracelet or the like, a unit including an inner approximately tubular member closed at one end and having a pair of alining slots extending lengthwise inwardly from its opposite end, an outer approximately tubular member fitting around and movable upon said inner member, said inner member being adapted to be fixed at its slotted end to the outer member of the next unit of the bracelet, a cross-piece on said outer member fitting in the slots of said inner member, said cross-piece being adapted to engage the end wall of said slots to limit the expanding movement of said outer member on said inner member, and a coiled spring disposed lengthwise within said inner member, said spring being interposed between the closed end of said inner member and said cross-piece and being compressed on expanding movement of said outer member on said inner member.

In testimony whereof, I have signed my name to this specification.

ABRAHAM SCHWARTZMAN.
